BACK GUARD CONTROL PANEL FOR A LAUNDRY MACHINE

Bertrand N. Trombley, Birmingham, Mich., assignor to
Borg-Warner Corporation, Chicago, Ill., a corporation
of Illinois

Application March 30, 1953, Serial No. 24,239

Term of patent 14 years

(Cl. D49—1)

To all whom it may concern:

Be it known that I, Bertrand N. Trombley, a citizen of the United States, residing in Birmingham, in the county of Oakland and State of Michigan, have invented a new, original, and ornamental Design for a Back Guard Control Panel for a Laundry Machine, of which the following is a specification, reference being had to the accompanying drawing, forming a part thereof, in which:

Fig. 1 is a front elevational view of a back guard control panel for a laundry machine embodying my new design;

Fig. 2 is an enlarged fragmentary, detailed view of the pattern illustrated on the lower panel of Fig. 1;

Fig. 3 is a sectional view of Fig. 1, taken along the

Fig. 4 is an elevation taken from the right end of Fig. 1.

I claim:

The ornamental design for a back guard control panel for a laundry machine, substantially as shown.
